UNITED STATES PATENT OFFICE.

FRANK L. ROXS, OF CHICAGO, ILLINOIS.

DOUGH MIXER.

Application filed December 3, 1923. Serial No. 678,145.

To all whom it may concern:

Be it known that I, FRANK L. ROXS, a citizen of the United States, residing at Chicago, in the county of Cook and State of Illinois, have invented a certain new and useful Improvement in Dough Mixers, of which the following is a specification.

My invention relates to dough mixing machines and the general object of the invention is to provide an organized mechanism which shall be substantial in build, positive and smooth in its action, and largely automatic.

Among the specific objects of the invention it is my purpose to provide means for automatically stopping the mixer carriage at the bottom of its descent and at the top of its rise.

Another object is to provide means for positively holding the tub in position while the mixing operation is taking place.

Another object is to provide improved mechanism for supporting the carriage and moving it up and down to bring the mixing arms out of and into the tub.

Another object is to provide means for relieving the carriage supports of the weight and vibratory movement of the carriage during the mixing operation, I accomplish this by employing cushioning springs on which the carriage descends when the mixers are lowered into the tub. The springs also have a tendency to reduce the jar incident to the starting of the upward movement of the carriage.

I accomplish my objects by the mechanism illustrated in the accompanying drawings, in which—

Figure 1 is a front elevation of the machine. Certain portions are broken away at the right side of the view for revealing some of the inner parts of the mechanism.

Figure 2 is an end elevation looking toward the left in Figure 1. In this view certain of the parts are broken away at the right for the sake of clearness in showing some of the inner parts of the machine.

Figure 3 is a plan view taken on the line 3—3 Figure 1.

Figure 4 is a sectional view taken on the line 4—4 Figure 3.

Like numerals denote like parts throughout the several views.

According to the design shown, the machine is mounted upon a base plate 1, which

supports the machine proper, and which also forms a platform onto which may be rolled the tub 2, which contains the dough. Rising from the four corners of the bed plate are posts 4 which are braced together at the upper end by beams 6. End frames or panels 8 are located at each end of the machine, these being provided with vertical guideways 10. These cooperate with gibs 12 mounted upon the carriage 14 which supports all of the main operating parts of the machine.

It will be noted by reference specially to Figures 2 and 3 that the machine is duplex, that is, it is adapted to take two tubs at a time. For each tub there are three mixer spindles 18 arranged vertically and mounted so as to rotate in bearings 20 mounted on the carriage. At the lower end the spindles are provided with arms or paddles 22 for mixing the dough. At the upper end the spindles are secured to bevel gears 24 by which they are rotated. These bevel gears mesh with pinions 26 fastened to horizontal shafts 28 journaled in bearings 30 mounted on the carriage. A power shaft 34 is also journaled in the carriage and driven by an electric motor 36. Said shaft is provided with a pinion 38 which meshes with a gear 40. A clutch 42 serves to connect and disconnect the driving gear 40 to and from a counter shaft 44, which is journaled on the carriage. This clutch, which is best shown in Figure 3, is controlled by means of a clutch lever 46 shown in elevation in Figure 1. The countershaft 44 drives one of the mixer shafts 28 by means of belts 48 and the other of said mixer shafts by means of pinions 50 and gears 52.

The mixer shafts 28 not only drive the mixer spindles but also serve to raise and lower the carriage. The mechanism for effecting this will now be described.

The corner posts 4, previously mentioned, have threaded portions 54. These are stationary and non-rotatable and form screws which cooperate with rotatable sleeves 56 shown in section in Figure 4. These sleeves are flanged at the bottom to support washers 58 which in turn support hubs 60 which form part of the carriage. It will be evident that by rotating the sleeves the carriage will be raised or lowered.

The sleeves are rotated by means of gears 62 which are keyed to them and by prefer-

ence separated from the hub 60 by washers 64. The gears 62 mesh with and are driven by gears 66 which are keyed to short upright shafts 68 provided with step bearings 70 formed in the carriage. Bevel gears 72 are also keyed to shafts 68. Clutch sleeves 74 are splined upon one of the mixer shafts 28 and are adapted to cooperate with either of two bevel gears 76, 78 which are loosely mounted on the shaft, although they are confined lengthwise thereon in the manner usual with bevel gear clutches. These bevel gears 76, 78 are permanently in mesh with the bevel gears 72. As the mixer shaft is power driven it will be evident that by shifting the clutch sleeve into mesh with one or the other of the bevel gears 76, 78 the bevel gears 72 will be rotated in one direction or the other and hence rotate the sleeves 56 in one direction or the other, depending upon the position of the clutch sleeves. The mixer shafts 28 are caused to rotate in unison by belts 79 and pulleys 81, as shown in plan in Figure 3.

28 The position of the clutch sleeves is controlled by forks 80 fastened to a clutch shifting rod 82. This rod is slideable in stationary bearings 84 and is controlled by a lever 86 which has a stationary fulcrum 88 between its ends and a roller 90 at its lower end. A stationary cam 92 is located in position to engage the roller 90 as the carriage descends and thus throw the lever 86 to such position that the clutch sleeves 74 will occupy neutral position. This will prevent the rotation of the mixer shafts 28 from being transmitted to the sleeves 56. Consequently the downward movement of the carriage will be automatically arrested. 40 This occurs when the mixing arms 22 are in acting position within the tubs.

45 The clutch sleeve 74 is shifted to neutral position also by a stationary cam 94 shown at the upper right corner of Fig. 1. This cam is located in position to engage the arm 80 fastened to the shifting rod 82. The result is that when the carriage rises to proper elevation to lift the mixing arms out of the tubs the clutch sleeve will be shifted to neutral position and thus discontinue the rotation of the sleeve 56 and terminate the upward movement of the carriage.

55 Projecting downward from the carriage are four elements 100 which may be regarded as dowel pins. These in descending pass through apertures 102 formed in brackets 104 secured to the sides of the tub as shown in elevation in Fig. 1. Stationary sockets 106 are mounted on the base plate 1 in position to receive the lower ends of the dowel pins and brace them against lateral movement. Thus when the carriage is lowered the tubs will be securely held against movement upon the base plate.

60 65 Sometimes when the mixing arms are in

action the tub has a tendency to rock upon its rollers 99. To prevent this I have placed slideable collars 101 upon the dowel pins 100 and have made these adjustable by securing them in desired position by set screws 103. 70 In practice these are adjusted to such position upon the dowel pins that when the carriage has descended to lowermost position the collars will rest upon the upper brackets 104 and thus prevent the tub from rocking. 75

I have provided cushioning means for supporting the carriage when it is down in acting position. These cushioning means include blocks 110 shown in end elevation in Figure 2, and in front elevation at the right end of Figure 1. These blocks are guided by stationary upright pin 112 and seat upon helical compression springs 114 which rest upon wings 116 of the end panels 8. In order to prevent the guide pins from interfering with the descent of the carriage, sockets 118 are formed in the under side of the overlying portions of the carriage as shown in dotted lines in Figure 2. The parts are so constructed and proportioned that when the carriage is down in operating position the weight of it will be carried partially or entirely by the springs, thus relieving the sleeves 56. It will be understood that when the mixing arms are rotating the tendency toward vibration exists to a considerable degree and the wear and tear on the parts are greatly reduced by thus transferring the weight of the carriage to the spring instead of having it carried by the rotatable sleeves 56.

Operation: Let it be assumed that the carriage is in raised position and the clutch sleeve 74 in neutral position as illustrated in the drawings. Let it be assumed also that the operator has thrown the main controlling lever 46 to a position which will cause the motor to drive the jack shaft 44, thus causing the dough mixing arm or paddle 72 to rotate. Let it also be assumed that the tubs are in position for use. The operator throws the lever 86 toward the right of Figure 1, thus shifting the clutch sleeves 74 toward the left and causing the sleeves 56 to rotate in a direction which will lower the carriage. The operator may then leave the machine, for, as the carriage approaches the lower end of its proper movement, the roller 90 at the lower end of the lever 86 comes into contact with the cam 92 and is thrown by the latter toward the left. This restores the clutch sleeves 74 to neutral position and terminates the rotation of the sleeves 56. Consequently the downward movement of the carriage ceases. The mixing arms are now in normal acting position and as they are rotating the machine may be left for such period as is required to complete the mixing action on the dough.

As the carriage descends the dowel pins 130

100 engage the apertured brackets 102 and prevent the tubs from changing their position. As previously intimated the carriage as it approaches its lowermost position comes 5 into contact with the cushioning blocks 110. Its downward movement is soon thereafter terminated but in the meantime the springs 114 will be compressed to such extent as to carry part or all of the weight of the carriage. This relieves the sleeves 56 and causes the jar incident to the operation of the mixing arms to be absorbed.

As soon as the dough has been worked long enough the operator throws the lever 15 86 toward the left to throw the clutch sleeves 74 toward the right Figure 1. This causes the sleeves 56 to be rotated in a direction to raise the carriage. As the carriage approaches the highest proper position the arm 20 96 on the clutch rod 82 comes into engagement with the stationary cam 94 which restores the clutch sleeves 74 again to neutral position. Thus it will be seen that the machine is largely automatic in its operation; 25 also that it is rugged in construction, the carriage being supported on four sleeves which rotate simultaneously. It will also be evident that the tubs will be securely and automatically held when the machine is in action, and that the jar of the dough mixers 30 will be largely absorbed by the springs.

In addition to the cushioning effect for the sleeves 56 the springs 114 relieve the gearing which controls the vertical position of 35 the carriage. When the carriage is in lowermost position the springs, of course, are under compression and when the clutch is thrown to move the carriage upward the springs will help start it upward with the 40 result that the pressure will be thrown onto the gearing gradually and thus the shock will be eliminated or at least greatly reduced.

Having thus described my invention what I claim as new and desire to secure by Letters Patent is:

1. A dough-mixing machine having a dough container, rotatable mixing arms, a vertically traveling carriage whereon said arms are mounted to be brought into and out 50 of the dough, carriage operating means for raising and lowering the carriage, and means controlled by the movement of the carriage for controlling said carriage operating means to thereby automatically terminating the vertical movement of the carriage.

2. A dough-mixing machine having a tub for the dough, rotatable mixing arms, a carriage traveling vertically and supporting said arms for moving them into and out of 55 the tub, carriage operating means including a power device and a clutch for rendering the power device operative and inoperative upon the remainder of the carriage operating mechanism, a clutch shifter on the carriage for controlling the clutch, and sta-

tionary means operative upon the clutch shifter for throwing out the clutch to limit the travel of the carriage.

3. A mixing machine having a tub for the dough, rotatable mixing arms, a vertically traveling carriage for supporting said arms, means on the carriage for rotating them, brackets on said tub and projections mounted on the carriage and adapted to engage said brackets when the carriage is lowered, 75 whereby the tub will be held stationary while the mixing arms are acting.

4. A mixing machine having a tub for the dough, brackets extending therefrom, a vertically movable carriage, rotatable mixing arms mounted upon the carriage in position to descend into the tub when the carriage is lowered, pins projecting downward from the carriage for engaging the bracket to hold the tub stationary during the mixing operation, and stationary sockets in position to receive the lower end of the pins for bracing them while they are holding the tub.

5. A dough mixing machine having a 90 tub, mixing arms, a carriage for moving the arms up and down out of and into the tub, arm driving mechanism carried by the carriage for rotating the arms, screw mechanism for raising and lowering the carriage, 95 and a power device common to the screw mechanism and the arm driving mechanism for operating both of them, said power device being mounted upon and movable with the carriage.

6. A dough mixing machine having a tub, mixing arms, a carriage for moving the arms up and down out of and into the tub, stationary upright screws, internally threaded sleeves cooperating with said screws, said sleeves supporting the carriage, and an electric motor mounted upon the carriage for rotating said sleeves in unison.

7. A dough mixing machine having a tub, mixing arms, a carriage for moving the arms up and down out of and into the tub, power mechanism on the carriage for rotating the arms, and cushioning springs for supporting the carriage at the lowermost position of travel, for absorbing the jar incident to the operation of the arms.

8. A dough mixing machine having a tub, mixing arms, a carriage for moving the arms vertically into and out of the tub, a power device on the carriage for rotating said arms, stationary upright screws, internally threaded sleeves working on said screws, the sleeves supporting the carriage and being rotated by said power device, and cushioning springs for supporting the carriage at the lowermost point of its travel, for relieving the sleeves of part of the weight of the carriage while the arms are acting.

9. A dough mixing machine having a tub, a vertically movable carriage, dough mix-

4
ing arms rotatably mounted on said carriage, means for rotating said arms, means for moving the carriage vertically, and means carried by the carriage and vertically movable with relation to it for overlying and engaging different portions of the tub when the carriage is in lowermost position, for preventing the tub from rocking.

10. A dough mixing machine having a tub supported upon rollers, dough mixing arms, a carriage for supporting said arms, means for rotating said arms, means supported by the carriage for moving it vertically, brackets on the tub, dowel pins on the carriage arranged vertically for engaging said brackets when the carriage is lowered, to prevent the tub from moving laterally during the mixing operation, and vertically adjustable collars mounted on said dowel pins and adapted to engage said brackets when the carriage is lowered, for preventing the tub from rocking upon its rollers during the mixing operation.

11. A dough-mixing machine having a tube, rotatable mixing arms, a carriage for moving the arms up and down out of and into the tub, screw mechanism for raising and lowering the carriage, a power device,

a clutch for connecting and disconnecting the power device to and from the screw mechanism, and clutch controlling mechanism operated by the movement of the carriage for throwing out the clutch to thereby automatically terminate the movement of the carriage.

12. A dough-mixing machine having a tub, rotatable mixing arms, a carriage for moving the arms up and down out of and into the tub, a power device mounted upon the carriage traveling with it and connected to said arms for rotating them, screw mechanism for raising and lowering the carriage, a clutch for connecting and disconnecting the screw mechanism to and from the power device, and clutch controlling mechanism part of which is stationary and part of which is mounted upon the carriage and travels with it in position to engage the stationary part, to be operated thereby for throwing out the clutch and thereby automatically terminating the movement of the carriage.

In witness whereof, I have hereunto subscribed my name.

FRANK L. ROXS.
